UNITED STATES PATENT OFFICE.

CHAUNCEY L. LANDON, OF AKRON, OHIO.

DESIGN FOR A TIRE-TREAD.

51,418.

Specification for Design.

Patented Oct. 23, 1917.

Application filed July 27, 1916. Serial No. 111,721. Term of patent 14 years.

To all whom it may concern:

Be it known that I, CHAUNCEY L. LANDON, a citizen of the United States, residing at Akron, in the county of Summit and State of Ohio, have invented a new, original, and ornamental Design for a Tire-Tread, of which the following is a specification, reference being had to the accompanying drawing, forming part thereof.

Figure 1 is a plan view of a portion of a tire showing my new design; and

Fig. 2 is a cross-sectional view of the tire.

According to my design, the tread of the tire bears a centrally located series of studs which are connected by a continuous rib. On each side of the studs of the central series is arranged a lateral series of connected studs bearing a staggered relation to the studs of the central series.

I claim—

The ornamental design for a tire tread as shown and described.

CHAUNCEY L. LANDON.
